UNITED STATES PATENT OFFICE.

DUNCAN D. McMILLAN, OF LA CROSSE, WISCONSIN.

IMPROVEMENT IN SELF-REGULATING GAS-BURNERS.

Specification forming part of Letters Patent No. 159,108, dated January 26, 1875; application filed November 21, 1874.

To all whom it may concern:

Be it known that I, DUNCAN D. McMILLAN, of La Crosse, in the county of La Crosse and State of Wisconsin, have invented a new and Improved Self-Regulating Gas-Burner, of which the following is a specification:

In the accompanying drawing, Figure 1 represents a vertical central section of my improved self-regulating gas-burner; and Fig. 2, a top view of the same with upper tip part detached, to show flexible diaphragm and gas-channel.

Similar letters of reference indicate corresponding parts.

My invention relates to an improved self-regulating gas-burner, by which uniformity of flow, exemption from leakage, and economy in the consumption of gas are combined with a simple, cheap, and durable construction. The invention consists of a gas-burner with flexible diaphragm and valve depending therefrom secured in position intermediately between the tip and base section of the burner, the lower chamber of the same being connected by suitable perforations with an annular channel concentric to the diaphragm, which channel conducts the gas to the delivery-tube in any position of the tip section by means of two or more channels, the flow being regulated in the customary manner by the pressure of the gas on the diaphragm and the corresponding opening and closing of the valve.

In the drawing, A represents the lower or base section, and B the upper or tip section, of my improved self-regulating gas-burner. The base-section A forms a cylindrical chamber, into which the lower conical part of the tip section is hermetically screwed. A flexible diaphragm, C, of leather or other suitable material, is interposed between the sections of the burner and secured in position by the same. It supports centrally the stem of a valve, D, which opens or closes in the usual well-known manner from below the entrance-aperture of the gas according to the pressure of the gas on the diaphragm. The diameter

of the cylindrical entrance-chamber is larger than that of the diaphragm, so that an annular channel, a, may be arranged concentric thereto around the same, into which the gas flows by two or more apertures, a', from the lower chamber, as is indicated by arrows in Fig. 1. Channel a is closed by the upper section, when the same is tightly secured and connected by two or more channels, b, in the conical part of the same, with its delivery-tube feeding the gas to the tip at any position of the upper section without necessitating any special adjustment of the same to the gas-conveying channels, as the communication is established uniformly and reliably as soon as the upper section is attached to the lower, which is a main point of my invention. The flow of gas is thereby evenly kept up and independently of the pressure of the gas on the diaphragm, so that a steady and uniform flame is obtained.

The regulating attachment may be kept within small compass, so as to be of ornamental appearance, and be used, furthermore, for supporting a glass globe for parlor and other purposes, if desired.

The self-regulating action and even flow of the gas to the delivery tube and tip furnish a reliable and economical burner for general application.

Having thus described my invention, I claim as new and desire to secure by Letters Patent—

The combination of the lower section or shell A, provided with a circumferential annular chamber, a, having bottom openings a', the top section having upwardly-converging channels b, and the flexible diaphragm C and valve D, secured between the two sections, and located inside the annular gas-chamber, as herein shown and described.

DUNCAN D. McMILLAN.
